MULTIPLE CAN PUNCH

Everett D. Armstrong and John M. Gresham,
Lufkin, Tex.

Application October 23, 1953, Serial No. 387,887

2 Claims. (Cl. 30—6.1)

1

This invention relates to improvements in can punches, and more particularly to a novel and useful device for punching more than one can at a time, the device being especially, but not exclusively for use by bartenders in taverns, bars, clubs and the like, the primary object of the invention being to provide an efficient and easily operable device of this character which enables quickly, accurately, and easily punching at one time a plurality of such cans as beer cans in order that the serving of beverages or the like may be facilitated and speeded up.

Another important object of the invention is to provide a device of the character indicated above which is foot-operated, so as to leave the hands of the operator free for attendant work, and so as to be more easily and conveniently operable than any hand-operated device, and which is adaptable to be mounted on a support, such as a counter, incorporated in a counter or bar, or to have its own floor-engaging support, such as a frame.

Other important objects and advantages of the invention will be apparent from the following description and the accompanying drawings, wherein, for purposes of illustration only, specific embodiments of the invention are set forth in detail.

Figure 1 is a left-hand side elevation, partly in transverse vertical section of one form of the invention, shown in operated condition in full lines;

Figure 2 is a top plan view of Figure 1;

Figure 3 is a front elevation;

Figure 4 is a left-hand side elevation showing the device in starting condition;

Figure 5 is a horizontal section taken on the line 5—5 of Figure 4; and

Figure 6 is a transverse vertical section, partly in side elevation, showing another form of the invention in starting or unoperated condition.

Referring in detail to the drawings, wherein like numerals designate like parts throughout the several views, and particularly to Figures 1 to 5 thereof, the device therein illustrated, and generally designated 7, comprises a stand 8 involving front corner legs 9, 9 and rear corner legs 10, 10, the front and rear legs 9 and 10 at the same sides of the frame being spaced and braced by horizontal stretcher bars 11, 11. The legs are preferably in the form of metal pipes but may be of any other suitable form and material.

The stand 8 is completed by side angle irons 12, 12 and front and rear angle irons 13 and 14, respectively, which are joined together by suitable

2

means, at the corners of the frame 8 at the upper ends of the legs, the angle irons being overlaid by a preferably metal plate 15, which is secured in suitable manner to the angle irons, and provides a substantially square table top.

Flat bar standards 16, 16 are secured at their lower ends in suitable manner to the outer sides of the depending flanges 17, 17 of the side angle irons 12, 12 and the standards 16, 16 have free upper ends 18, 18 through which are journaled the related ends of a shaft or axle 19 which extends between the standards parallel to the table top plate 15. Retaining collars 20, 20 and washers 20', 20' are positioned on the shaft 19 at the outer sides of the standards 16, 16 and are provided with set screws 21, 21 securing them to the shaft 19.

A radial lever arm 22 fixed to a middle part of the shaft 19 extends in a rearward direction 20 and has a free rear end 23 which reaches rearwardly beyond the stand 8. A vertical connecting rod or pitman 24 has an upper end pivoted to the free end 23 of the lever 22, as indicated at 25, and has a lower end pivoted, as indicated at 26, to the rear free end 27 of a foot-operated lever 28, having a treadle 29 on its forward end.

The foot-operated lever 28 is fixed, by means of a collar 30 having a set screw 31, on an intermediate part of a shaft or axle 32 whose opposite ends are journaled through the stretcher bars 11, 11 at points between and spaced from the front and rear stand legs 9, 9 and 10, 10. Cotter pins 33, 33 are secured on the ends of the shaft 32 at the outer sides of the stretched bars 11, 11. The treadle 29 preferably reaches forwardly beyond the front of the stand 8, as shown in Figures 2, 4 and 5.

A stretched contractile spring 35 is secured at its upper end, as indicated at 36, to a part of the lever arm 22 at a point near the rear end thereof, and at its lower end to a rear part of the table top plate 15, as indicated at 37, for returning the lever arm 22, and hence the shaft 19 to a retracted starting or unoperated position, from an operated position.

Fixed, as by welding, to the underside of the shaft 19 and projecting tangentially therefrom in a forward direction, are two similar cutter carrying plates or bars 38, 38 which are spaced from each other along the shaft 19 and are spaced from the standards 16, 16.

The cutter carrying bars 38, 38 have longitudinal slots 39, 39 through which rise studs 40, 40 located near opposite ends of punch or cutter plates 41, 41 engaging the undersides of the bars

38, 38, and wing nuts 42, 42 are threaded on the studs 40, 40 and clampingly engage the upper sides of the bars 38, 38 and provide for longitudinal adjustment of the cutter plates 41, 41 relative to the bars 38, 38.

On the forward ends of the punch or cutter plates 41, 41 are downwardly and forwardly directed declining relatively small punches or blades 43, 43 of inverted triangular shape, as shown in Figure 3, and provided with cutting edges 44, 44.

On the rear ends of the cutter plates 41, 41 are similar, larger, and right angularly arranged blades or punches 45, 45.

Extending across the table top plate 15 between the standards 16, 16 at the forward edges of the standards 16, 16 and secured thereto in suitable manner, is a vertical backing plate 47, which rises to a level close to the underside of the shaft 19 or to a level in the region of the upper ends 48, 48 of cans 49, 49 placed upon the table top plate 15, beneath the punch plates 41, 41.

Semi-circular positioning and guiding flanges 50, 50 are secured in suitable manner to and rise from the table top plate 15, in concentric relation to the centers of the cutter plates 41, 41 are secured together at their laterally inward ends, as indicated at 51. The laterally outward ends of the flanges 50, 50 are rounded or outwardly curved, as indicated at 52, to facilitate and guide the entry of cans 49, 49 into proper position within the flanges 50, 50 and into proper relationship to the punch plates 41, 41, so that as the punch plates 41, 41 are swung downwardly from the starting position, shown in Figure 4 to the operated position shown in Figure 1, the front and rear blades 43, 43 and 45, 45 will punch the tops 53, 53 of the cans 49, 49 at diametrically opposed and spaced points, the rear larger blades 45, 45 entering first, followed by the smaller front blades 43, 43.

The above described operation of the punch plates 41, 41 is produced simply by stepping downwardly upon the treadle 29. The cans 49, 49, properly punched, can then be removed, practically upon release of the treadle 29, because the spring 35 acts quickly to restore the punch plates to elevated retracted starting position.

Referring now to the form of the invention shown in Figure 6 of the drawings, and generally designated 7a, the stand 8a is in the form of a bar counter having a counter or bar top T, and vertical supports 9a, all supported on a floor F. In this instance a table top member resting upon and secured to the bar top T comprises a table top plate 15a supported on depending flanges 17a. The standards 16a, 16a rise from the outer sides of the flanges 17a, and the remainder of the mechanism is the same as the form of Figures 1 to 5 of the drawings, with the exceptions that the pitman 24a passes downwardly through a hole H provided in a rear part of the bar top T, and the foot-operated lever 28a is pivotally mounted on bracket means 11a fixed to and rising from the floor F.

What is claimed is:

1. In a multiple can punch, a support, a table top structure including a table top plate, said structure being on an upper part of said support, standard means fixed on said structure and rising above said table top plate, first rotary horizontal shaft means journaled on said standard means and having a fixed lever arm projecting from one side thereof, multiple cutter carrying bars spaced

along said shaft means and projecting from another side of said shaft means and over said table top plate, punch plates mounted on said carrying bars having punch blades thereon, second horizontal rotary shaft means journaled on said support below said table top structure, a foot-operated lever pivoted at a point intermediate its ends on said second shaft means, a treadle on one end of said foot-operated lever, a vertical pitman having an upper end pivoted to said lever arm and having a lower end pivoted to the other end of said foot-operated lever, and retracting spring means stretched between said lever arm and a part of said table top structure, said multiple cutter carrying bars comprising at least two laterally spaced cutter carrying bars each having a punch plate thereon, each of said punch plates having spaced blades thereon, said table top plate having semi-circular guide flanges rising thereon in concentric relation to the punch plates for positioning cans concentrically beneath the punch plates on said table top plate, the punch blades of the punch plates being positioned to punch two holes in the top of each of the cans present within the guide flanges on the table top plate at the same time as the treadle is depressed from an elevated position.

2. In a multiple can punch, a support, a table top structure including a table top plate, said structure being on an upper part of said support, standard means fixed on said structure and rising above said table top plate, first rotary horizontal shaft means journaled on said standard means and having a fixed lever arm projecting from one side thereof, multiple cutter carrying bars spaced along said shaft means and projecting from another side of said shaft means and over said table top plate, punch plates mounted on said carrying bars having punch blades thereon, second horizontal rotary shaft means journaled on said support below said table top structure, a foot-operated lever pivoted at a point intermediate its ends on said second shaft means, a treadle on one end of said foot-operated lever, a vertical pitman having an upper end pivoted to said lever arm and having a lower end pivoted to the other end of said foot-operated lever, and retracting spring means stretched between said lever arm and a part of said table top structure, said multiple cutter carrying bars comprising at least two laterally spaced cutter carrying bars each having a punch plate thereon, each of said punch plates having spaced blades thereon, said table top plate having semi-circular guide flanges rising thereon in concentric relation to the punch plates for positioning cans concentrically beneath the punch plates on said table top plate, the punch blades of the punch plates being positioned to punch two holes in the top of each of the cans present within the guide flanges on the table top plate at the same time as the treadle is depressed from an elevated position, one of the punch blades of each punch plate being smaller than the other.
